US00D999067S

(12) **United States Design Patent** (10) **Patent No.:** **US D999,067 S**
(45) **Date of Patent:** **** Sep. 19, 2023**

(54) **PEELABLE PACKAGE**

(71) Applicant: **Church & Dwight Co., Inc.**, Princeton, NJ (US)

(72) Inventors: **Michael T. Pinchiaroli**, Martinsville, NJ (US); **Richard James Elliott Gilbert**, Belle Mead, NJ (US); **Jonathan Andrew Wharton**, Ewing, NJ (US); **James Bernard Oldham**, Chester, VA (US)

(73) Assignee: **Church & Dwight Co., Inc.**, Princeton, NJ (US)

(**) Term: **15 Years**

(21) Appl. No.: **29/773,590**

(22) Filed: **Mar. 10, 2021**

(51) LOC (14) Cl. **09-05**

(52) U.S. Cl.

(57) **CLAIM**

The ornamental design for a peelable package, as shown and described.

DESCRIPTION

FIG. 1 is a perspective view of an embodiment of a peelable package according to the present invention showing our new design;

FIG. 2 is another perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof;

FIG. 8 is a bottom view thereof;

FIG. 9 is a perspective view of a second embodiment of the peelable package according to the present invention showing our new design;

FIG. 10 is another perspective view thereof;

FIG. 11 is a front view thereof;

FIG. 12 is a rear view thereof;

FIG. 13 is a side view thereof;

FIG. 14 is an opposite side view thereof;

FIG. 15 is a top view thereof;

FIG. 16 is a bottom view thereof;

FIG. 17 is a perspective view of a third embodiment of the peelable package according to the present invention showing our new design;

FIG. 18 is another perspective view thereof;

FIG. 19 is a front view thereof;

FIG. 20 is a rear view thereof;

FIG. 21 is a side view thereof;

FIG. 22 is an opposite side view thereof;

FIG. 23 is a top view thereof;

FIG. 24 is a bottom view thereof;

FIG. 25 is a perspective view of a fourth embodiment of the peelable package according to the present invention showing our new design;

FIG. 26 is another perspective view thereof;

FIG. 27 is a front view thereof;

(Continued)

FIG. 28 is a rear view thereof;
 FIG. 29 is a side view thereof;
 FIG. 30 is an opposite side view thereof;
 FIG. 31 is a top view thereof; and,
 FIG. 32 is a bottom view thereof.
 The broken lines shown herein depict portions of the peelable package that form no part of the claimed design.
